[57] CLAIM

The ornamental design for a golf club holder, as shown and described.

DESCRIPTION

FIG. 1 is a perspective view of a golf club holder showing my new design;

FIG. 2 is a top plan view of the first and third embodiments;

FIG. 3 is a perspective view of FIG. 1; shown in broken away condition for convenience of illustration;

FIG. 4 is a top plan view of the second embodiment;

FIG. 5 is a perspective view of a second embodiment of a golf club holder; and,

FIG. 6 is a perspective view of a third embodiment of a golf club holder.

The broken line showing of clubs and golf bags is for illustrative purpose and forms no part of the claim. The bottom not disclosed of all the embodiments is not a part of a claim.

1 Claim, 2 Drawing Sheets
